Primary Examiner — Anhdao Doan*Assistant Examiner* — Mary Shannon Malley(74) *Attorney, Agent, or Firm* — McCarter & English, LLP; Matthew R. Van Eman(57) **CLAIM**

The ornamental design for a canister-type device for tissue processing, as shown and described.

DESCRIPTION

FIG. 1 is a perspective view of a canister-type device for tissue processing.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top view thereof; and,

FIG. 7 is a bottom view thereof.

The broken lines show portions of the canister-type device for tissue processing that form no part of the claimed design.
